UNITED STATES PATENT OFFICE.

J. PARKER PRAY, OF NEW YORK, N. Y.

DESIGN FOR A FINGER-NAIL POLISHER.

SPECIFICATION forming part of Design No. 19,185, dated June 25, 1889.

Application filed January 24, 1889. Serial No. 297,434. Term of patent 7 years.

To all whom it may concern.

Be it known that I, J. PARKER PRAY, a citizen of the United States, residing at New York, county and State of New York, have invented 5 a new and original Design for Finger-Nail Polishers, of which the following is a specification, reference being had to the accompanying drawings, which form part of the same.

This invention relates to devices used in 10 manicure treatment for polishing finger-nails; and it consists in a novel shape or configuration to be imparted to such devices.

The accompanying drawings illustrate a finger-nail polisher shaped in accordance with 15 my design.

Figure 1 is a front elevation; Fig. 2, an end elevation, and Fig. 3 an underneath plan view.

My design relates to the portion of a finger-nail polisher which may be designated the 20 "body," lettered *a*, *b*, and *d* in the drawings.

This design is composed of two elements or characters, which are to be used in combination. The first element consists in the shape or configuration of the block or back forming 25 the foundation for the pad, having parallel

sides and rounded ends, and a slight and gracefull longitudinal curve shown in the front elevation, Fig. 1, which, in combination with the transverse curvature of the back shown in the end elevation, Fig. 2, gives a pleasing 30 and tasteful finish. The second or main element of the combination consists in the shape of the pad *a*, having the outline of the polishing-face composed of parallel sides and rounded ends, and the slightly-hollowed surface which follows the configuration of the back, as shown in Fig. 1. All the corners and edges of the design are rounded. The relative dimensions may be slightly varied without changing the character of the design. 35

Having now described my invention, what I claim, and desire to secure by Letters Patent, is—

The design for finger-nail polishers, as herein shown and described.

J. PARKER PRAY.
